UNITED STATES PATENT OFFICE.

CLIFFORD E. DUNN, OF NEW YORK, N. Y., ASSIGNOR TO GILLETTE SAFETY RAZOR COMPANY, A CORPORATION OF MASSACHUSETTS.

SAFETY-RAZOR.

1,064,457.

Specification of Letters Patent. Patented June 10, 1913.

Application filed May 25, 1907. Serial No. 375,586.

To all whom it may concern:

Be it known that I, CLIFFORD E. DUNN, a citizen of the United States, residing in the city of New York, borough of Brooklyn, county of Kings, and State of New York, have invented certain new and useful Improvements in Safety-Razors, of which the following is a full, clear, and exact specification.

This invention relates to safety razors, such as are adapted particularly for use in connection with flexible blades, although they can be used with other kinds of blades if desired.

The objects of the invention are to improve and simplify the construction of such devices; furthermore, to increase their efficiency in use, and to decrease the expense attending their manufacture.

With the foregoing and other objects in view, which will appear as the description proceeds, the invention resides in the combination and arrangement of parts and in the details of construction hereinafter set forth, it being understood that changes in the precise embodiment of invention herein disclosed can be made within the scope of the following claims without departing from the spirit of the invention.

In the accompanying drawings forming part of this specification, Figure 1 is a side elevation of a safety razor constructed in accordance with the invention. Fig. 2 is a similar view, partly in section. Fig. 3 is a plan view of the guard. Fig. 4 is a side elevation showing a slightly modified construction. Fig. 5 is a view taken at a right angle to Fig. 4.

The reference numeral 1 in Fig. 2 represents a guard or clamping member which, as shown in Fig. 3, is provided along its opposite edges with teeth 2. The guard 1 is also formed adjacent its center with a rectangular opening 3, and adjacent its ends with circular openings 4. The numeral 5 indicates a cap or clamping member, which is adapted to coöperate with the clamping member 1 for the purpose of clamping a razor blade against the same. The guard 1 and cap 5 are preferably in practice transversely curved, for the purpose of flexing the razor blade 6. The cap or clamping member 5 is shown provided with a pair of positioning pins 7, located in position to

extend through suitable perforations in the 55 razor blade 6 and through the openings 4 in the guard 1, for the purpose of positioning the razor blade in the usual manner.

A cam construction is illustrated for adjustably forcing the clamping members 1 60 and 5 together and locking them in their adjusted positions. The clamping cam is shown pivotally supported on one of the clamping members. In the embodiment of invention herein disclosed the clamping cam 65 or locking device 8 is shown pivotally mounted at 9 between a pair of ears or lugs 10 carried by the cap 5. When the parts are in the position shown in Fig. 2 the locking device 8, together with the ears 10, will project through the opening 3 in the guard 1. The cam face 11 of the locking device 8 is located in position to engage the under surface 12 of the guard 1. The formation of the cam may be such that it will remain 70 in its position of adjustment or some co-operative locking device may be employed. The handle 14 of the locking device 8 is shown constructed for engagement with a series of teeth 15, which are shown formed 75 integrally upon a curved portion or yoke 16 connected with the guard 1, and with the handle 17 of the razor. By moving the locking device 8 in the direction of the arrow in Fig. 2, the cam face 11 engages the 80 underface 12 of the guard 1 and draws the cap 5 against the guard 1, thereby flexing the razor blade 6 and clamping it in position. The degree to which the blade shall be flexed can be regulated by engaging the 85 handle 14 with the appropriate tooth of the series of teeth 15, as will be readily understood.

The modified construction shown in Figs. 4 and 5 is exactly the same as the construction shown in Figs. 1 to 3, except that the cap 5' is provided at the opposite ends thereof with downwardly extending arms 20, in which are formed longitudinal slots 21, traversed by bolts or screws 22 connected 90 with the guard 1'. The slotted arms 20 serve to provide a yielding and pivotal connection between the guard and cap, which connection permits said members to be separated sufficiently to permit the insertion 95 and removal of the razor blade without permitting said members to become entirely detached from each other.

The improved razor of the present invention is strong, simple, durable, and inexpensive in construction, as well as thoroughly efficient in operation.

5 What is claimed is:

1. A safety razor having a pair of blade clamping members, a rack connected with one of said members, and a pivotally-mounted locking device connected with the other 10 of said members and having its free end located in position to engage said rack for locking said members together.

2. A safety razor comprising a guard having a central opening therein, a handle 15 having a yoke-shaped portion connected with said guard and provided with a curved rack, a cap having a pair of lugs and a locking device pivotally mounted between said lugs having a cam portion, said locking device being adapted to extend through the 20

opening in said guard and to be engaged with its free end with said curved rack.

3. A safety razor having a pair of clamping members adapted to flex a thin razor blade, one of said members having an opening therein, a pivotal locking device connected with the other of the said members extending through said opening, and a rack fast with one of said members and located in position relatively to the free end of said pivotal locking device so as to be engaged thereby. 25 30

In testimony whereof, I have hereunto set my hand in the presence of two subscribing witnesses.

CLIFFORD E. DUNN.
